UNITED STATES PATENT OFFICE.

BENJAMIN C. HOEFER, OF KANSAS CITY, MISSOURI.

COIN-DELIVERING MACHINE.

1,268,462.

Specification of Letters Patent.

Patented June 4, 1918.

Application filed June 4, 1914. Serial No. 842,833.

To all whom it may concern:

Be it known that I, BENJAMIN C. HOEFER, a citizen of the United States, residing at Kansas City, in the county of Jackson and State of Missouri, have invented a certain new and useful Improvement in Coin-Delivering Machines, of which the following is a full, clear, concise, and exact description, reference being had to the accompanying drawings, forming a part of this specification.

My invention relates to coin delivering machines, that is, devices of that class wherein selective ejecting mechanism is associated with a magazine for coins or other tokens.

My present invention may be considered as an improvement over the machines described in my copending applications, Serial No. 629,593, filed May 26, 1911, and Serial No. 686,062, filed March 25, 1912, which have resulted in Patents Nos. 1,105,516 and 1,105,517 respectively both granted July 28th, 1914.

My present invention contains special features over those of my previous patents, which may be tabulated as follows:

(1) The number and arrangement of keys;
(2) The lock release; and
(3) The interlocking arrangement.

In the machines of my previous patents, referred to, about 100 keys were employed and by these machines it is possible to secure the change up to any amount by depressing the key indicating that amount. In that type of machine, only comparatively few of the keys are given a great deal of usage and my present invention is concerned with an improved keyboard and related arrangement thereof, whereby the number of keys is greatly reduced and the entire machine is correspondingly simplified.

While with my present machine, as with my former machines, it is possible to secure any desired amount of change quickly, accurately and readily, in my present machine certain odd amounts are selected by depressing two keys at the same time. I have found by experience that one may become proficient in handling my present machine more quickly than my former machine, since there are fewer keys to choose from, even though more than one in some instances have to be pressed in order to secure the desired

amount. Never more than two keys are required to be pressed at the same time.

It is the theory, therefore, of my new keyboard that I provide a set of keys ranging from 1 to 10 in units, and from 5 to 100 in multiples of 5, special keys being provided to secure a dollar in change, or a half-dollar in change, or ten cents in change. Naturally, the interior mechanism is very much simplified and the number of parts greatly reduced and, not only is the efficiency of the machine not impaired, but it is really improved.

The lock release may be briefly described by stating that automatic means is provided for locking the ejectors for individual magazines when they have been emptied so that at no time may a key be depressed without securing the full amount of change. When, however, the machine is to be emptied, it is desired that this lock shall not be operative, since the ejectors are then simply feeders and are not counted on as change selectors and it is therefore, desired that under these circumstances the lock be released. For such or analogous conditions, I have, therefore, provided means to this end.

The interlock to which I have referred comprises an arrangement for preventing the actuation of a second key before an initially operated key, or two keys, having completed its or their stroke, thus preventing any miscalculation if items of change were to be added.

I shall continue the description of my invention by reference to the accompanying drawings, in which—

Figure 1 is a front elevational view of my machine, the casing being removed to reveal the interior construction;

Fig. 2 is a plan view of the keyboard;

Fig. 3 is a side elevational view;

Fig. 4 is a cross-sectional view;

Fig. 5 is an isolated rear view of some of the mechanism; and

Figs. 6, 7, 8 and 9 are various views of the interlocking mechanism.

Referring first to Figs. 1, 2 and 3, it will be seen that I provide a main casing 10, which has the forwardly projecting part 11, the top of which forms the keyboard. The entire machine preferably is set on standards 12, 12. The front of the machine tilts backward slightly, as plainly shown in Fig. 3, and at the top and front thereof the coin

magazine 13 is mounted. This magazine comprises a plurality of upright channels 14, 14, which are made in various sizes so as to accommodate coins of different denominations. The particular machine from which the drawings are made is adapted for United States money, but it will appear that coins of any kind may be used. This magazine is provided at the rear with a pair of lugs, 15, 15, which are drilled for the reception of a standard 16 extending upwardly from the top of the casing to support the magazine, as illustrated in Figs. 1 and 3.

As illustrated in Fig. 4, the magazine 13 is provided with a bottom 17, upon which the columns of coins rest, the magazine being so formed that the lowermost coin or coins, as will be pointed out presently, may be ejected therefrom and thrown downwardly into a hopper 18, disposed below the magazine and mounted upon forwardly extending posts 19, 19, secured upon the front of the casing 10. The hopper directs the coins down to an opening in the bottom thereof, illustrated in dotted lines at 20 and this opening is normally covered by a closure 21 held in normal position by gravity and adapted to be lifted by engaging the under side of the finger piece 22. It will be noted that this finger piece and the hopper are directly above the keyboard and very close to it, so that great convenience of operation of the machine is obtained. After manipulating one or two of the keys, it requires but a turn of the hand to engage the finger piece 22 and raise the closure 21 to allow the coins to drop out of the hopper.

As described in my above mentioned patents, the ejector mechanism comprises a plurality of U-shaped bars 23, which are nested one within the other and which are all mounted upon a common shaft 24 mounted in the end plates of the casing, as clearly shown in Figs. 1 and 4. There is one of these U-shaped bars provided for each of the channels, for each of which an ejector is provided. The horizontally extending part of each of the bars 23 has secured thereto a bracket 24', which leads upwardly to a position in back of the lower end of the magazine. At 25, on each of these bars, an ejector 26 is pivotally mounted. This ejector is in the form of an arm extending forwardly from the pivot 25 and through a slot 27 in the casing and a slot 28 in the lower end of the magazine, as shown in Fig. 4. This lever is counterbalanced and is held in its uppermost position by means of the other arm thereof, which is weighted, as indicated at 29. The ejector is adapted and arranged to engage the lowermost coins, or in two instances the two lowermost coins, and it will be seen that it is necessary to carefully adjust the height at

which the front end of the ejector rests in its normal position. This is done by means of an adjusting screw 30, which is mounted in a bracket 31, secured to the inside of the casing, a lock nut 32 being provided to hold the adjusting screw in any adjusted position. One of these adjusting screws is provided for each ejector and the front arm of the ejector is normally held against the under side of its screw by means of the weight on the other arm.

Mounted upon each of the pivots 25 is a lock arm 33, which extends forwardly through the slots 27 and 28 and extends into the lower end of the corresponding compartment of the magazine, and extends upwardly above the bottom, as illustrated in Fig. 4, when that particular channel is empty and is held down flush with the top of the bottom when the channel is properly filled. The rear part of the member 33 is provided with a weight 34, which holds the forward end of this locking arm in its uppermost position. It will be noted that this locking arm is provided with a shoulder or hook 35, which, when the parts are in their normal position and when the corresponding channel is empty, engages with a shoulder 36 on the inside of the casing. It will be clear that when the locking arm 33 is depressed, the hook 35 will be disengaged from the shoulder 36 and the locking arm, with the ejector, is permitted to be moved forwardly by means which will be described presently. Each of the keys 37 is mounted upon the shaft 24 and extends forwardly and upwardly through appropriate slots in the casing, and on the outside is provided with a finger piece 38. Integral with each key is a rearwardly extending plate 39, upon the forward end of which the "code" 105 is formed, that is, the forward edge of each of the plates 39 is so formed, as illustrated in Fig. 4, as to select and engage a particular bar 23, or more than one of them, so that the corresponding ejectors for the necessary coins to make up the amount which is indicated by the related key may be actuated by the downward pressure on the key. Thus, the foremost plate, illustrated in Fig. 4, selects and is adapted to engage the 110 fourth and fifth U-bars, and these particular U-bars are arranged to throw a five cent piece out of each of the five cent coin containers. Thus, the key which is related with this particular plate is the key *a* of Fig. 2, 120 which has the indication "10" thereon. It will be seen that when any key is depressed, the corresponding U-bars will be carried forwardly and with them the proper ejectors and locking bars. If any of the selected channels are not properly filled, the locking bar will be engaging the shoulder which has been referred to and it will be

impossible to depress the key and the warning is thereby given to the operator. The forward movement of the U-bars is limited by the engagement of the shoulder 40 with the cross bar 41, illustrated in Fig. 4.

It will be noted that each of the locking bars 33 is provided with a hump 41', above which and in line with which a rectangular bar 42 is pivotally mounted. The trunnions 10 43 for this bar are mounted in the side plates of the casing and one of them is provided with a handle 44 so that, if it is desired to release the locking mechanism, this can be done by moving the handle in the direction 15 of the arrow x . This will throw the bar 42 into the position shown in dotted lines in Fig. 4 and will force down the locking bars to a point where the hooks thereon will be disengaged from the shoulders 36.

20 A shaft 45 extends from end to end in the back part of the casing 10, and this shaft has hanging thereon at each end two quadrant members 46, 46. The shaft itself is mounted between two frame pieces 47, 47, 25 which are mounted by means of posts 48, 48 upon the inside of the casing. These quadrants form part of the locking mechanism which has been referred to. Attached to each of the quadrant members 46 is another quadrant 49 and, since the quadrant set on one side is like that on the other, I shall refer to but one of them. The quadrant 49 is provided with a circular slot 50, in which a pin 51 engages. This pin is 30 mounted upon a bracket 52, secured to a U-shaped bar 53, mounted upon a pivot member 54. This bar is adapted to be engaged by each of the plates 39, when it is actuated by its key, so that the bracket 52 and its pin 51 will be swung around the pivot 54. This will bring the quadrants 46 and 49 forwardly, as illustrated in Fig. 9. Each of the quadrants is provided with ratchet teeth on the circular portion there- 35 of and the teeth on one quadrant extend in an opposite direction from the teeth on the other quadrant. The teeth on the quadrant 49 are adapted to be engaged by a pawl 55 mounted on the pivot member 54, this pawl 40 being adapted to be held in engaging position by means of a weight 56. The teeth on the quadrant member 46 are adapted to be engaged by a pawl 57, which is mounted upon a pivot member 58 and is adapted to 45 be held in engaging position by means of a weight 59. The normal position of these parts is with the pawl 55 engaging its teeth while the pawl 57 is out of engagement with its teeth. With this condition of parts, the 50 depression of a key is possible, since the ratchet teeth 49' on the quadrant member 49 may slide over their pawl, while the other pawl is out of engagement with its teeth. However, when the key has completed its 55 stroke, and not till then, a pin 60 on the

quadrant 49 engages a pawl thrower 61, pivoted at 62, and moves it in the direction of the arrow y , as indicated in Fig. 9. This action causes the pawl thrower 61 to engage a pin 63 on the pawl 55 and to disengage it 70 from the teeth 49'. At the same time, a pin 64 on the quadrant member 46 engages another pawl thrower 65, pivoted at 66, which pawl thrower has been holding the pawl 57 out of engagement with the teeth 46' on the 75 quadrant member 46, by its engagement with a pin 67 on the pawl 57, and moves it out of this holding engagement so as to permit the pawl 57 to move into operative relation with the teeth 46'. Thus, the parts are 80 all in position for the return stroke of the key, which takes place upon the release thereof under the influence of gravity. It is thus necessary in each instance to complete the entire stroke of the key before it 85 may be moved back.

It will be noted that a bar 68 extends between the two quadrant members 49 and it will be noted also that, when the quadrant member is drawn forward by the actuation 90 of one key, or two keys, this bar will be thrown into position so that, if it is attempted to actuate any other key, or if any other key is pressed accidentally, this false actuation will be prevented, because the rear extension 39' on each of the plates 39 will engage with the under side of this bar 68. It is, therefore, impossible, after a key has 95 been actuated, or two keys substantially simultaneously actuated, for another key 100 to be actuated later in the stroke, and false operation is thereby effectively prevented.

A manual release member 69 is mounted upon a shaft 70, which has the handle 71 on the outside of the casing. This release member 105 engages with the pawl 55, which is normally in engagement with its teeth, to release it from this engagement, if such release is desired.

I shall now refer to the keyboard, which 110 is illustrated in Fig. 2. In order to facilitate key selections, I use vari-colored press buttons, and it will be noted that I provide unit numbers from one to ten in red and numbers from five to ninety-five in multiples of five in white, and also four buttons in blue. The blue button which is marked "100" calls for one dollar in change, and the blue button which is marked "50" calls 115 for fifty cents in change, while the blue button which is marked "25" calls for twenty-five cents in change. The blue button which is marked "10" calls for two nickels. The white button which is marked "5" calls for a nickel, and the white button which is 120 marked "\$" calls for a silver dollar. The red button which is marked "5" calls for five pennies.

I find by experience that the combination which I provide in this way is a very effi- 125

cient one and is extremely simple, since only thirty-three keys and levers are employed. By this means, not only is any amount from one cent to one dollar secured in the least 5 number of coins, but special arrangements, such as ten cents in two nickels, or five cents in pennies, or one dollar in change, or fifty cents in change or twenty-five cents in change, may be secured. It is necessary to 10 press only one button at a time unless some amount other than a multiple of five is desired and, in that case, the operation is to press one of the white buttons in the second row and also one of the red buttons in the 15 first row, preferably simultaneously. Thus, if twenty-three cents were desired, one would press the twenty cent key and the three cent key at the same time; for forty-eight cents, one would press the forty cent 20 key and the eight cent key, at the same time, etc.

The keyboard is therefore especially simple in places of business where pennies are not needed and is effectively simple even 25 though pennies are needed, since the keys which are most used are not distributed throughout a maze of keys which are used very infrequently.

It will be clear that the interlocking feature and the lock release feature may be omitted without interfering with the useful 30 features of the specific form of keyboard and I have, therefore, drawn the appended claims so as to cover the keyboard whether 35 the interlocking feature and the release feature are employed or not.

I claim:

1. In a change making machine a plurality of coin magazines, an ejector for each 40 magazine, a keyboard containing keys each for operating one or more of said ejectors, means for locking any of said ejectors when the corresponding magazine is substantially empty and means for releasing said locking 45 means, there being two keys for each coin denomination, one for ejecting a coin of

such denomination and one for ejecting the amount of the denomination in change.

2. In a change-making machine, a plurality of coin magazines, an ejector for each 50 magazine, means for operating said ejectors, means for locking any of said ejectors when the corresponding magazine is substantially empty, and means for releasing said lock, said means having a handle exterior of said machine.

3. In a change-making machine, a plurality of coin magazines, an ejector for each magazine, means for operating said ejectors, automatic devices for locking any of said 60 ejectors when the corresponding magazine is not filled, and a bar for simultaneously releasing all of said devices.

4. In a change-making machine, a plurality of coin magazines, a reciprocating ejector 65 for each magazine, a locking bar moving with said ejector and extending into the bottom of the magazine, a hook on said bar adapted to engage a stationary part to prevent movement of the bar and ejector, the 70 weight of the coins holding said bar out of said engagement, and a member normally out of engagement with said bar for moving said bar out of its locking position.

5. In a change-making machine, a plurality of coin magazines, a reciprocating ejector for each magazine, a locking bar moving with said ejector and extending into the bottom of the magazine, a hook on said bar adapted to engage a stationary part to prevent 80 movement of the bar and ejector, the weight of the coins holding said bar out of said engagement, and a rotatable releasing rod for moving said bar out of its locking 85 position.

In witness whereof, I hereunto subscribe my name this 29th day of May, A. D., 1914.

BENJAMIN C. HOEFER.

Correction in Letters Patent No. 1,268,462.

It is hereby certified that in Letters Patent No. 1,268,462, granted June 4, 1918, upon the application of Benjamin C. Hoefer, of Kansas City, Missouri, for an improvement in "Coin-Delivering Machines," an error appears in the printed specification requiring correction as follows: Page 4, line 54, claim 2, after the word "means" insert the words *independent of the coins*; and that the said Letters Patent should be read with this correction therein that the same may conform to the record of the case in the Patent Office.

Signed and sealed this 9th day of July, A. D., 1918.

[SEAL.]

W. H. CLAY,

Acting Commissioner of Patents.
